UNITED STATES PATENT OFFICE.

ARTHUR J. LECK, OF TROY, NEW YORK, ASSIGNOR TO EARL & WILSON, OF TROY, NEW YORK, A CORPORATION OF NEW YORK.

DESIGN FOR A LABEL-BLANK.

43,426.

Specification for Design.

Patented Jan. 7, 1913.

Application filed October 21, 1912. Serial No. 727,088. Term of patent 14 years.

To all whom it may concern:

Be it known that I, ARTHUR J. LECK, a citizen of the United States, residing at Troy, in the county of Rensselaer and State of New York, have invented a new, original, and ornamental Design for Label-Blanks, of which the following is a specification, reference being had to the accompanying drawing, forming part thereof.

The single figure of the drawing is a plan view of a label-blank, showing my design.

I claim:

The ornamental design for a label-blank, herein shown.

ARTHUR J. LECK.
